Primary Examiner — Derrick Holland(74) *Attorney, Agent, or Firm* — Seed IP Law Group PLLC(57) **CLAIM**

The ornamental design for a wind turbine blade, as shown and described.

DESCRIPTION

FIG. 1 is an isometric view of a wind turbine blade showing my new design.

FIG. 2 is a front elevation view thereof.

FIG. 3 is a rear elevation view thereof.

FIG. 4 is a top plan view thereof.

FIG. 5 is a bottom plan view thereof.

FIG. 6 is a left side elevation view thereof; and,

FIG. 7 is a right side elevation view thereof.
